ATTACHMENT MEANS FOR VENETIAN BLINDS

William O. Roberts, Austin, Tex., assignor of ten percent to N. O. Roberts, Austin, ten percent to George Roberts, ten percent to Ed O'Neal Coleman, ten percent to James Coleman, and ten percent to Charles C. Roberts, Houston, Tex.

Application August 25, 1955, Serial No. 530,445

3 Claims. (Cl. 160—173)

This invention relates to new and useful improvements in attachment means for venetian blinds.

An object of this invention is to provide new and improved means for attaching the lower bar of a venetian blind to the sides of a window frame.

An important object of this invention is to provide new and improved attachment means for pivotally attaching the lower bar of a venetian blind to a window frame to permit swinging of said bar from about the level of the window sill to an elevation higher than that of the window sill without detaching said attachment means from the bar, whereby the lower end of the venetian blind can be raised for cleaning said window sill, for operating a casement window crank, or for similar purposes.

Another object of this invention is to provide an adjustable anchor means for the lower bar of a venetian blind, which is so constructed that the bar, or either end thereof, can be elevated from the window sill to a predetermined elevation thereabove, and can be maintained at said elevation or at any selected position between said window sill and said predetermined elevation.

Still another object of this invention is to provide a new and improved attachment means for attaching a lower bar of a venetian blind to a window frame, wherein said attachment means includes a member pivotally connected to each side of said lower bar and to the sides of the window frame for permitting pivotal movement of said bar, and wherein the members are formed of a resilient or spring material and are so spaced from each other that they apply an inward force to each side of said lower bar to maintain said bar at selected positions above the window sill to the extent permitted by said pivotal movement and without requiring disconnection of said members from said lower bar.

A further object of this invention is to provide a new and improved attachment means for a venetian blind which is so constructed that improved ventilation is obtained when using same with a venetian blind by permitting the lower end of the blind to be positioned at a higher elevation than that of the window sill, while at the same time applying a positive retaining force to the lower end of the blind to normally prevent same from dropping or flopping back and forth in the wind.

The construction designed to carry out the invention will be hereinafter described, together with other features thereof.

The invention will be more readily understood from a reading of the following specification and by reference to the accompanying drawings forming a part thereof, wherein an example of the invention is shown, and wherein:

Figure 1 is a fragmentary elevational view of the lower portion of a window having a venetian blind installed therein, illustrating the attachment or anchor means of the invention connected to the blind and to the frame of the window and showing the blind as it appears when its lower edge is disposed horizontally and positioned immediately above the window sill;

2

Figure 2 is a view similar to Figure 1, but showing the blind with its lower bar raised to the full extent permitted while the attachment means is still connected;

Figure 3 is a view similar to Figure 1, but showing the blind with its lower bar tilted to permit access to a casement window crank;

Figure 4 is a fragmentary perspective view showing one form of the attachment or anchor means of this invention; and

Figure 5 is a fragmentary exploded view showing another form of the attachment or anchor means of this invention.

Referring to Figures 1-3 of the drawing, a portion of a conventional casement type window is shown, the window having a frame 1 with vertical side faces 1a and a horizontal window sill 1b. A pair of windows 2 are mounted in the frame in the usual manner by hinges (not shown) and are arranged to swing outwardly upon manipulation of one of the two cranks 3. The window has a venetian blind installed therein, the blind being of the usual construction and having a plurality of horizontally disposed slats 4 which are connected by two pairs of tapes 5. The lower ends of the tapes 5 are attached to a horizontally disposed lower bar 6, which is positioned below the lowermost slat 4.

The attachment or anchor means of the invention consists of a pair of members or strips 7, each of which is formed of an inherently resilient material, such as spring steel. Each strip 7 is preferably curved intermediate its ends so that the end portions thereof lie in different planes which are parallel to and spaced apart from each other. One end of each strip 7 is pivotally connected to an end face or side of the bar 6, and the opposite end of each strip 7 is pivotally connected to the adjacent vertical side face 1a of the frame 1. As will be evident hereinafter, the arrangement is such that the ends of the bar 6 may be swung outwardly and upwardly from its position immediately above the window sill 1b as shown in Figure 1 to the raised position shown in Figure 2, or to any selected intermediate elevation. Also the bar 6 may be tilted at the angle shown in Figure 3 or at the opposite angle if desired, without disconnecting the strips 7 from the bar 6. When the bar 6 is in the raised position (Figure 2) the window sill 1b is easily available for cleaning, and also upon opening the windows 2, ventilation below the blind is provided without disconnecting the blind from the members 7. The tilting of the blind (Figure 3) is ordinarily used when it is desired to manipulate only one of the cranks 3, and again it will be observed that the bar does not become disconnected from the members 7.

The end portions of the strips 7 which have connection with the bar 6 yieldably engage the side faces 1a of the frame 1 and the end faces of the bar 6, respectively, to which they are connected, and therefore the bar 6 is held in any of the positions shown in Figures 1-3, or at any selected intermediate position, so that a positive retaining force is applied to the lower end of the blind to normally prevent same from flopping back and forth when a wind blows against same.

As shown in detail in Figure 4, a screw 8 extends through an opening 8a in the inner end of each strip 7 for threading into the vertical side face 1a of the vertical window frame 1 (Figures 1-3) whereby each strip 7 is pivotally connected to one of the side faces 1a. The opposite end portion of each strip 7 has a hole 9 formed therein for engagement by a pin 10 which is connected to the side or end face of the bar 6 and extends outwardly therefrom whereby each strip 7 is pivotally connected to one of the end faces of the bar 6.

As previously mentioned, the members or strips 7 apply an endwise force to the bar 6 at all times which is sufficient to hold the bar 6 in a raised position so that it

does not drop or flap back and forth. To obtain such endwise force, the members 7 are made of a resilient or spring material and the outer ends of the pair of strips 7 are spaced from each other a lesser distance than the length of the bar 6 prior to attaching the bar 6 to the strips 7. Thus, it is necessary to expand the strips 7 away from each other to position the pins 10 in the openings 9 of the strips 7. By curving the strips 7, as shown in the drawings, so that the outer ends are disposed closer to each other than the inner ends thereof when the strips 7 are attached to the window frame 1 and the bar 6, the pins 10 can project through the openings 9 without contacting the frame 1, and also the frictional engagement of the strips 7 with the frame 1 is concentrated at the inner ends of the strips. Such concentration of the frictional engagement at the inner ends of the strips also results from the lever action imparted to each strip due to its inherent resiliency and its confined position under compression between the side face of the window frame 1 and the end of the bar 6. Such frictional engagement is not sufficient to interfere with the swinging of the bar 6, but it is sufficient to prevent the bar 6 from being moved by the wind from a selected elevation at which it is positioned.

A modified form of the strip 7 is shown in Figure 5, which is similar to that form shown in Figure 4, but in the form of Figure 5, a pin 11 is attached to, or is integral with, the outer end of the strip 7 and extends laterally therefrom for positioning in a hole 12 formed in each of the end faces of the bar 6 for pivotal connection thereto. Thus, in instances where the bar 6 is provided with openings 12 instead of pins 10, the members 7 of Figure 5 are used instead of the members 7 of Figure 4; but both function in the same manner in providing the pivotal connection of the bar 6 to the window frame 1.

It should be noted that in both forms of the invention illustrated, the members 7 are pivotally connected to the vertical side faces 1a of the window frame which eliminates the accumulation of dust and dirt on the horizontal surface of the window sill 1b which occurs with the attachment means presently used for venetian blinds.

It will be understood that this invention can be used with any type of window, and that the casement window is illustrated only because the attachment means of this invention is particularly advantageous for use on blinds mounted in casement windows due to the tilting feature previously described which provides quick access to the cranks for opening and closing the casement windows.

The foregoing disclosure and description of the invention is illustrative and explanatory thereof and various changes in the size, shape and materials, as well as in the details of the illustrated construction, may be made within the scope of the appended claims without departing from the spirit of the invention.

What is claimed is:

1. In combination with a window having a venetian blind installed therein, means for anchoring the lower bar of the blind to the sides of the window frame, comprising a pair of elongated flat metal strips connected, respectively, to the ends of the bar, each of the strips being formed of a material characterized by its inherent re-

silience and being curved intermediate its ends so that the end portions thereof lie in different planes parallel to and spaced apart from each other, one end of the strip being pivotally connected to an end face of the bar and the opposite end of the strip being pivotally connected to the adjacent side face of the frame, the arrangement being such that the connected ends of the bar, or either end thereof, may be swung outwardly and upwardly to a selected position from a lowermost position in which the bar is disposed horizontally and is positioned immediately adjacent the window sill, the strips yieldably engaging the faces to which they are connected and being confined under compression therebetween for maintaining the bar in its selected position.

2. An attachment means for attaching the lower bar of a venetian blind to a window frame, including a pair of attachment members, means pivotally connecting one end of each of said members to the opposite vertical side faces of the window frame, means pivotally connecting the other end of each of said members to the opposite ends of said lower bar whereby said lower bar is pivotally connected to said window frame for swinging said lower bar upwardly from its lower position immediately above the window sill to an upper elevation permitted by the length of each said members, each of said members being formed of a resilient material and being confined under compression between the vertical side face of the window frame and the end face of the bar so that each of said members applies an endwise force to the bar and in a direction towards each other to thereby hold said bar at any selected position between said window sill and said upper elevation.

3. An attachment means for attaching the lower bar of a venetian blind to a window frame, including a pair of attachment members, means pivotally connecting one end of each of said members to the opposite vertical side faces of the window frame, means pivotally connecting the other end of each of said members to the opposite ends of said lower bar whereby said lower bar is pivotally connected to said window frame for swinging said lower bar upwardly from its lower position immediately above the window sill to an upper elevation permitted by the length of each of said members, each of said members being formed of a resilient material and said other ends of said members being spaced apart a distance less than the length of said lower bar prior to the connection of said other ends of said members to said bar so that said members are expanded and confined under compression between the vertical side face of the window frame and the end face of the bar, whereby each of said members applies an endwise force to the bar to hold said bar at any selected position between said window sill and said upper elevation.
